US00D694201S

(12) **United States Design Patent**
Iino(10) **Patent No.:** **US D694,201 S**
(45) **Date of Patent:** **** Nov. 26, 2013**(54) **LIGHT-EMITTING DIODE**(71) Applicant: **Citizen Electronics Co., Ltd.**,
Fujiyoshida (JP)(72) Inventor: **Takashi Iino**, Kofu (JP)(73) Assignees: **Citizen Electronics Co., Ltd.**,
Yamanashi-Ken (JP); **Citizen Holdings
Co., Ltd.**, Tokyo (JP)(***) Term: **14 Years**(21) Appl. No.: **29/433,495**(22) Filed: **Oct. 1, 2012**(30) **Foreign Application Priority Data**

Mar. 30, 2012 (JP) 2012-007632

(51) **LOC (9) Cl.** ..... **13-03**(52) **U.S. Cl.**USPC ..... **D13/180**(58) **Field of Classification Search**USPC D13/180; D26/1; 257/79, 80, 81, 88,
257/89, 95, 98, 99, 100, E33.058; 313/483,
313/498, 500; 362/555, 800

Primary Examiner — Selina Sikder

(74) Attorney, Agent, or Firm — Browdy and Neimark,
PLLC(57) **CLAIM**The ornamental design for a light-emitting diode, as shown
and described here.**DESCRIPTION**FIG. 1 is a perspective view of a light-emitting diode showing
my new design, with an upper surface, a front side surface and
a right side surface;FIG. 2 is a perspective view showing a bottom surface thereof
with a left side surface and a rear side surface;

FIG. 3 is a front elevation view thereof;

FIG. 4 is a rear elevation view thereof;

FIG. 5 is a top plan view thereof;

FIG. 6 is a bottom plan view thereof;

FIG. 7 is a left side elevation view thereof; and,

FIG. 8 is a right side elevation view thereof.
